[57] CLAIM

The ornamental design for a flag case, as shown and described.

DESCRIPTION

FIG. 1 is a front elevational view of a flag case showing my new design; the rear elevational view being a mirror image thereof;

FIG. 2 is a right side elevational view thereof, the left side elevational view being a mirror image thereof;

FIG. 3 is a top plan view thereof; and,

FIG. 4 is an exploded perspective view thereof.

The broken line showing of flag is for illustrative purpose only and forms no part of the claim.

FIG. 2

FIG. 1

FIG. 3
